PROCESS AND APPARATUS FOR ARTIFICIALLY RECONSTITUTING DAYLIGHT

Filed Sept. 17, 1923

Fig.2.

Fig. 4.

Fig. 3.

Fig. 5.

A circular diagram divided into 12 equal sectors. Each sector is labeled with a number: 2, 3, or 4. The labels are distributed as follows: 2 appears 5 times, 3 appears 6 times, and 4 appears 1 time. The sectors are arranged in a repeating pattern of 2, 3, 3, 2, 3, 3, 4, 3, 2, 3, 2, 3 starting from the top.

INVENTOR:

Charles Henri Alfred Gémain

ATTORNEY

UNITED STATES PATENT OFFICE.

CHARLES HENRI ALFRED GAMAIN, OF PARIS, FRANCE.

PROCESS AND APPARATUS FOR ARTIFICIALLY RECONSTITUTING DAYLIGHT.

Application filed September 17, 1923. Serial No. 663,232.

To all whom it may concern:

Be it known that I, CHARLES HENRI ALFRED GAMAIN, citizen of the Republic of France, residing at Paris, France (post-office address 82 Rue Compans), have invented certain new and useful Improvements in Processes and Apparatus for Artificially Reconstituting Daylight, of which the following is a specification.

10 The present invention relates to the production of artificial daylight; and its object, stated briefly, is to provide an improved lamp or equivalent lighting apparatus or device which is constructed in such a way as to overcome the defects inherent in apparatus of the character indicated now in use.

These defects, as is generally known, primarily involve distortion of colors and 20 strains upon the eyes, and they are chiefly due to differences in the spectral composition of natural and artificial light, the latter being characterized by the presence of the red and yellow rays in increased quantity and by 25 a decrease in the blue-green and violet rays. It has been proposed to correct these defects in various ways; but, so far as I am aware, such attempts have heretofore been unsuccessful.

30 According to my invention, however, an artificial light is produced which has, to all intents, the same, or substantially the same, spectral composition as daylight; this result being obtained by means of the apparatus hereinafter described. The improved 35 apparatus which, therefore, constitutes the subject matter of the invention, comprises an electric lamp bulb of blue-tinted glass filled with argon or other gas of like character and 40 operating under a higher voltage than that for which the lamp is designed; such bulb having associated with it a special arrangement of reflecting mirrors and, in combination therewith, a filter and a screen.

45 The effect of the high voltage of the current passing through the lamp filament is to heat the latter to a greater degree of incandescence than occurs in the standard half-watt lamps, so that the lamp is thereby 50 caused to emit an increased quantity of blue rays, in order to bring the spectrum of its light nearer to the spectrum of natural daylight. The blue tinting of the glass, on the other hand, has the effect of intercepting the 55 orange-yellow rays which are still emitted

in great number in spite of the increased incandescence of the filament.

As to the reflecting mirrors, these are silvered and are arranged in one or more circular rows concentrically around the bulb, and some of them are colorless while others are of different colors ranging from blue-green to light violet; the purpose being not only to obtain the maximum efficiency by reflecting, with the least possible amount of absorption, all the rays which have not been intercepted by the colored glass of the bulb, but also to obtain a much whiter artificial light than has heretofore been obtained. This light still differs, however, from natural daylight in that the latter has a tendency toward the violet; and it is to correct that fault that the filter and screen mentioned above are utilized, the filter comprising a very thin glass plate interposed in the path of the light which is tinted or colored violet throughout, said plate intercepting only a very small portion of the useful rays, without the interposition of opal or blue-tinted glass. If necessary, it can be faced with a plate of lead glass in order to intercept the greatest portion of the ultra-violet rays which may be present in the light emitted by the overcharged filament; the light finally obtained by the combination of the above-mentioned features being identical with natural light in so far as concerns its spectral composition (visible rays) and producing neither color-distortion nor eye-strain.

In the accompanying drawings, two embodiments of an illuminating apparatus or lamp constructed in accordance with the invention are shown.

Figure 1 of said drawings is an elevation of the improved apparatus.

Figs. 2 and 3 are, respectively, a vertical section and a plan view of a reflector comprising a single row of mirrors, the lamp bulb also being illustrated in Fig. 2.

Figs. 4 and 5 are, respectively, an elevation and a plan view of a multi-row reflector.

Referring more particularly to the drawings, 1 (Fig. 2) indicates the blue-tinted bulb of the lamp proper, the filament of which is designed to be traversed by a current of higher voltage than that for which it was originally constructed. The voltage may, for example, be about 5 to 10% higher

than the normal one, so that a lamp intended for a current of 105 volts may be subjected to a current of 110 volts, or one constructed for use with a current of 210 volts 5 may be used with a 220 volt current. The said bulb is filled with argon or other similar rare atmospheric gas, as previously stated, and it is encircled by the reflector, which latter may consist either of a single 10 row of plane reflecting mirrors (Figs. 2 and 3) or a plurality of such rows (Figs. 4 and 5).

In either case, the reflecting mirrors include certain ones which are of uncolored 15 glass, indicated at 2, and others which are constructed either of blue-tinted glass (indicated at 3) or of violet glass (designated 4); all of the mirrors being silvered and coated with a substance which permits them 20 to resist the high heat radiated by the bulb. The mirrors are disposed at an angle to the vertical which varies according to the result sought. In the construction shown in Figs. 2 and 3, the angle in question is approximately 37° 30'; but while good results have 25 been obtained therewith, that particular angle is mentioned merely by way of example. For apparatus of high power (400 to 3000 C. P.), it is preferable to adopt a construction such as that represented in Figs. 4 and 30 5, in which the reflector comprises three concentric rows of mirrors arranged, respectively, at angles of 27°, 40° and 66° 30' to the vertical; these angles likewise being 35 given merely as examples. Speaking generally the arrangement of the mirrors and the angles at which they are disposed will depend largely upon whether a concentrating 40 or a dispersing action upon the rays is required and the extent of such action, for it will be apparent that the converging rays reflected by the mirrors may either be concentrated on a point at a desired distance, or may be distributed over a surface the 45 size of which depends upon the power of the apparatus and upon its height above the surface to be illuminated.

The filter interposed in the path of the 50 reflected rays is indicated at 5 (Fig. 2) and, as previously stated, consists of a thin plate of violet-colored glass, beneath which there is disposed the lead glass screen 6; the respective functions of said parts being to increase the content of violet rays in the light 55 passing through the filter (i. e., to increase the tendency of that light toward the violet and thus bring its spectral composition still closer to that of daylight) and to intercept the ultra-violet rays.

60 The above assemblage (that is to say, the bulb, its reflector and the associated filter and screen) is mounted within a casing or frame 7 which may have the form illustrated in Fig. 1, for example, or any other desired form, and which may be provided with

ventilation openings 9 arranged in one or more rows at suitable points or in some other preferred manner; the object being to insure free circulation of air around the bulb and between the latter and the reflecting 70 mirrors, so as to counteract the injurious effects of the abnormal voltage upon the life of the bulb.

The invention, as above described, may be utilized for any purpose where a light 75 identical with daylight is necessary or desirable; for instance, for illuminating drawing tables, operating tables, etc. It is particularly useful for surgical purposes, and especially for surgery of the eye; and when 80 used in that connection, as well as in others, it may be combined with any suitable optical system.

I claim as my invention:—

1. An illuminating apparatus for producing artificial daylight, comprising an electric light bulb colored blue throughout and containing an incandescent filament designed to be traversed by a current of higher voltage than that for which it was constructed; and a reflector encircling said bulb and embodying a row of silvered glass mirrors disposed at an incline to the vertical, certain of said mirrors being colorless and others being colored in shades of blue and 95 violet.

2. An illuminating apparatus for producing artificial daylight, comprising a colored electric bulb containing an incandescent filament designed to be traversed by a current of higher voltage than that for which it was constructed; and a reflector encircling said bulb and embodying a row of silvered glass mirrors inclined to the vertical, certain of the mirrors being colorless and others colored. 105

3. An illuminating apparatus for producing artificial daylight, comprising an electric light bulb colored blue throughout and containing an incandescent filament designed to be traversed by a current of higher voltage than that for which it was constructed; a reflector encircling the bulb and embodying a row of silvered glass mirrors inclined to the vertical, certain of the mirrors being colorless and others being colored in shades of blue and violet; and a violet filter interposed in the path of the light reflected by said mirrors. 110 115

4. An illuminating apparatus for producing artificial daylight, comprising an electric light bulb colored blue throughout and containing an incandescent filament designed to be traversed by a current of higher voltage than that for which it was constructed; a reflector encircling the bulb and embodying a row of silvered glass mirrors inclined to the vertical, certain of the mirrors being colorless and others being colored in shades of blue and violet; and a violet filter inter- 120 125 130

posed in the path of the light reflected by said mirrors and having a screen of lead glass disposed beneath its under face.

5. An illuminating apparatus for producing artificial daylight, comprising a colored electric light bulb containing an incandescent filament designed to be traversed by a current of higher voltage than that for which it was constructed; a reflector encircling 10 the bulb and embodying a row of silvered glass mirrors inclined to the vertical, certain of the mirrors being colorless and others colored; and a violet filter interposed in the path of the light reflected by said mirrors.

- 15 6. An illuminating apparatus for produc-

ing artificial daylight, comprising a colored electric light bulb containing an incandescent filament designed to be traversed by a current of higher voltage than that for which it was constructed; a reflector encircling 20 the bulb and embodying a row of silvered glass mirrors inclined to the vertical, certain of the mirrors being colorless and others colored; and a violet filter interposed in the path of the light reflected by said mirrors 25 and having a screen of lead glass disposed beneath its under face.

In testimony whereof I affix my signature.

CHARLES HENRI ALFRED GAMAIN.
